Gilbert Geer Troy New York.
Letters Patent (Design No 119) dated May 1st 1847

The schedule referred to in these Letters Patent and making part of the same.

To all whom these presents shall come. Be it known that I Gilbert Geer of Troy in the County of Rensselaer and State of New York, have invented or produced a new design for Stoves and that the following is a full and exact description of the same, reference being had to the accompanying drawings making a part of this Specification.

The design is intended to be cut in bold relief and is composed of several Gothic Arches sunk or depressed, the cavities of which is filled in with Crop Bars or diamond work (a a a a a a) with a projecting cornice having bold Gothic ornaments (b b) the base is elevated and depressed (c c). The recesses of which is filled in with fancy ornaments (e e e e e) and the projections with Rosettes (d d d d d d d)

I claim as my invention and desire to secure by Letters Patent the above design which is fully set forth in the Drawings accompanying this description
